CAP CLEANING AND STRETCHING BLOCK

Fritz Greifenhain, New York, N. Y.

Application August 1, 1942, Serial No. 453,161

5 Claims. (Cl. 223—24)

This invention relates to new and useful improvements in a cap cleaning and stretching block.

More specifically, the invention proposes the construction of a cap cleaning and stretching block formed of separate sections and arranged to be engaged into a cap in a manner to shape and stretch the same during washing and drying to prevent the cap from shrinking.

Another object of the invention proposes the formation of the sections in such a manner that when they are put in in a predescribed manner they will have an outer contour coinciding with the shape of the cap within which they are to be used.

It is another object of the invention to so construct the sections that when the last section is engaged into the cap it will simultaneously force each of the other sections into their completely extended shaping position and at the same time lock the other sections in position within the cap until such time as the last inserted section is removed from the cap.

A still further object of the invention proposes a means for limiting interengagement of the block sections in a manner to prevent their expansion beyond a point in which the cap is properly expanded and shaped.

A modification of this invention proposes the provision of a means for holding the last block section to be inserted into the cap securely in position in a manner to prevent its accidental disengagement from the cap.

Still another object of this invention proposes the construction of a cap cleaning and stretching block which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a cap having a cleaning and stretching block constructed in accordance with this invention.

Fig. 2 is a vertical sectional view taken on the line 2—2 of Fig. 1.

Fig. 3 is a vertical sectional view taken on the line 3—3 of Fig. 1.

Fig. 4 is a perspective view of the forward central block section per se.

Fig. 5 is a side elevational view of Fig. 4.

Fig. 6 is a vertical section taken on the line 6—6 of Fig. 4.

Fig. 7 is a perspective view of the locking rear central block section per se.

Fig. 8 is a side elevational view of Fig. 7.

Fig. 9 is a vertical sectional view on the line 9—9 of Fig. 7.

Fig. 10 is a vertical sectional view on the line 10—10 of Fig. 7.

Fig. 11 is a perspective view of one of the side block sections per se.

Fig. 12 is an end elevational view of Fig. 11.

Fig. 13 is a side elevational view of Fig. 11.

Fig. 14 is a sectional view on the line 14—14 of Fig. 11.

Fig. 15 is a bottom plan view of a cap having a cleaning and stretching block constructed in accordance with a modification of this invention.

Fig. 16 is a partial vertical sectional view taken on the line 16—16 of Fig. 15.

Fig. 17 is a side elevational view of the locking rear central block section looking in the direction of the line 17—17 of Fig. 15.

Fig. 18 is a partial horizontal sectional view taken on the line 18—18 of Fig. 17.

The cap cleaning and stretching block, according to this invention, is to be used in combination with a cap 10 and includes a pair of side block sections 11, a forward central block section 12 and a locking rear central block section 13 which are designed to be engaged into the cap as shown in Figs. 1 to 3. These block sections may be constructed of hard non-porous woods, metal, various plastics or other materials capable of shedding water.

The pair of side block sections 11 are alike in construction, and each has its outer face 14 shaped to contour of the sides of the cap 10, see Fig. 3. The inner faces 15 of the side block sections slope slightly inwards from the top to the bottom.

The forward central block section 12 is engaged in position between the front ends of the side block sections 11 and has its front face fashioned to the contour of the front of the cap 10, see Fig. 2. This central block section 12 has its side walls 17 sloping inwards from the top to the bottom to engage the inner faces of the front ends of the side block sections 11 to force the front ends of the side block 11 apart into facial contact with the inside of the cap 10. The block section 12 also has its rear face 18 sloping rearwards from the top to the bottom.

The locking rear central block section 13 is engaged in position between the rear ends of the

side block sections 11 and has its rear face 19 fashioned to the contour of the rear of the cap 10. The sides 20 of the rear central block section 13 slope inwards from the top to the bottom to engage the inner faces of the rear ends of the side block sections 11 to force the rear ends of the side block section apart into facial contact with the inside of the cap 10. The rear block section 13 has its front face 21 sloping rearwards from the top to the bottom to engage the sloping rear face of the front block section 12 to spread the central block sections to urge their outer faces 16 and 19 into facial contact with the front and rear areas of the cap 10.

The inner face 15 of each of the side block sections 11 is formed with a central recess 22 which has its ends sloping outwards from the top to the bottom. The side walls 17 of the front central block section 12 are formed with outwardly extending projections 23 for engaging within the front portions of the recesses 22. The front edges of the projections 23 are sloped outwards from the top to the bottom to agree with the contour of the front ends of the recesses 22. Likewise, the side walls 20 of the locking rear central block section 13 are formed with outwardly extending projections 24 for engaging within the rear portion of the recesses 22. The rear edges of the projections 24 are sloped outwards from the top to the bottom to agree with the contour of the rear ends of the recesses 22.

Each of the block sections 11, 12 and 13 has its bottom face concaved with the outer edges of all the block sections being in a common plane, see Figs. 2 and 3. This concaved bottom face causes any water which passes through the top of the cap 10 during the washing operation to be collected in the low point of the concaved face. The central front block section 12 has its rear face 18 formed with a groove 25 extended from its top to its bottom. In the assembled position of the blocks this groove 25 forms a space between the adjacent faces of the blocks 12 and 13 through which the water collected within the concaved bottom face of the block sections is adapted to discharge.

The rear central block section 13 is formed with a recess 26 extended inwards from its top face and into which one is adapted to engage one's finger to get a grip on this block section permitting it to be pulled from the cap 10 after it has thoroughly dried after being washed to free the block sections 11 and 12 to also be taken out of the cap 10.

The operation of this form of the invention is as follows:

Then the cap 10 becomes dirty and it is necessary to wash the same, it is laid upon a flat surface with its open bottom directed upwards. The side blocks 11 are then engaged into the cap 10 followed by the blocks 12 and 13 as shown in Fig. 1. The cap with the block sections in position therein is turned over and the entire outer surface of the cap is washed to remove the dirt. Any water which passes through the cap 10 will collect within the inverted concaved bottom face of the block sections and pass outward through the groove 25. After the washing operation is completed the cap 10 with the block sections still in position therein is placed aside to dry. The block sections will act to prevent the cap from shrinking while drying. After the cap is dried the locking central block section 13 is removed by inserting one finger in the recess 26 to grip this block section to facilitate its withdrawal to free

the block sections 11 and 12 to also be taken out of the cap 10.

In the modification of the invention shown in Figs. 15 to 19, means is provided for locking the rear central block section 13 in position with relation to one of the side block sections 11 to prevent this rear block section 13 from dropping out of the cap and so retain the block sections securely in position within the cap 10.

10. The means comprises a small metallic container 30 having a ball 31 urged outwards by an expansion spring 32. The container 30 is mounted within an elongated opening 33 formed in one side wall of the rear central block section 13 with the ball 31 projecting beyond this side wall to engage a recess 34 formed in the adjacent side wall of the side block section 11. The inner portion of the container 30 has an outwardly extending flange 35 disposed within the opening. 15 Serrations 36 are formed on the face of the flange. A strip 37 engages a portion of the flange 35 along one side of the opening 33 and has serrations 38 on its inner face. The serrations 36 and 38 are arranged to engage each other for locking the container 30 in a position in which the ball 31 will engage the recess 34 when all the block sections are engaged within the cap 10 with all faces in the same plane flush. The strip 37 is releasably retained in position by 20 means of screws 39 and in the loosened position of the screws 39 the container 30 will be free. Adjustment of the vertical position of the container 30 enables the ball 31 to be located at a proper position to engage the recess 34.

25. In other respects this form of the invention is similar to the previous form and like reference numerals identify like parts in each of the several views.

30. While I have illustrated and described the preferred embodiments of my invention, it is to be understood that I do not limit myself to the precise constructions herein disclosed and the right is reserved to all changes and modifications coming within the scope of the invention as 35 defined in the appended claims.

Having thus described my invention, what I claim as new and desire to secure by United States Letters Patent is:

1. A cap cleaning and stretching block, comprising a pair of side block sections for engaging into a cap and having their outer faces fashioned to the contour of the sides of said cap and having their inner faces sloping slightly inwards from the top to the bottom, a spreading forward central block section engaging between the forward ends of said side block sections and having its front face fashioned to the contour of the adjacent end of said cap and having its sides sloping inwards and engaging the inner faces of said 50 side block sections for spreading the latter block sections and further having its rear face sloping rearwards from top to bottom, and a locking rear central block section engaging between the rearward ends of said side block sections and having its rear face fashioned to the contour of the adjacent end of said cap and having its sides sloping inwards and engaging the inner faces of said side block section and further having its front face sloping rearwards from top to 55 bottom and engaging the rear face of said forward central block section for spreading said central block sections and means for locking said rear central block section in position with relation to one of said side block sections to prevent its accidental disengagement from said cap.

2. A cap cleaning and stretching block having a pair of side block sections with their outer faces fashioned to the contour of the sides of a cap and central block sections engageable between said side block sections and having their outer faces shaped to the contour of said cap, said side block sections having their inner faces sloping slightly inwards from the top to the bottom and said central block sections having their sides sloping slightly inwards from top to bottom to engage the sides of said side block sections and spread them against the sides of said cap, said side block sections being formed with central recesses having their ends sloping outwards from the top to the bottom, and projections formed on the sides of said central block sections and having their ends sloping outwards from the top to the bottom and engaging said recesses so that the sloping ends of said projections and recesses retain said central block sections from spreading beyond the ends of said side block sections.

3. A cap cleaning and stretching block, comprising a pair of side block sections for engaging into a cap and having their outer faces fashioned to the contour of the sides of said cap and having their inner faces sloping slightly inwards from the top to the bottom, a spreading forward central block section engaging between the forward ends of said side block sections and having its front face fashioned to the contour of the adjacent end of said cap and having its sides sloping inwards and engaging the inner faces of said side block sections for spreading the latter block sections and further having its rear face sloping rearwards from top to bottom, and a locking rear central block section engaging between the rearward ends of said side block sections and having its rear face fashioned to the contour of the adjacent end of said cap and having its sides sloping inwards and engaging the inner faces of said side block sections and further having its front face sloping rearwards from top to bottom and engaging the rear face of said forward central block section for spreading said central block sections and means for locking said rear central block section in position with relation to one of said side block sections to prevent its accidental disengagement from said cap, comprising a spring pressed ball mounted in the side of one of said sections and engageable with a complementary recess formed in the other block section.

4. A cap cleaning and stretching block, comprising a pair of side block sections for engaging into a cap and having their outer faces fashioned to the contour of the sides of said cap and having their inner faces sloping slightly inwards from the top to the bottom, a spreading forward central block section engaging between the forward ends of said side block sections and having its front face fashioned to the contour of the adjacent end of said cap and having its sides

- sloping inwards and engaging the inner faces of said side block sections for spreading the latter block sections and further having its rear face sloping rearwards from top to bottom, and a locking rear central block section engaging between the rearward ends of said side block sections and having its rear face fashioned to the contour of the adjacent end of said cap and having its sides sloping inwards and engaging the inner faces of said side block sections and further having its front face sloping rearwards from top to bottom and engaging the rear face of said forward central block section for spreading said central block sections and means for locking said rear central block section in position with relation to one of said side block sections to prevent its accidental disengagement from said cap comprising a spring pressed ball mounted in the side of one of said sections and engageable with a complementary recess formed in the other block section, a container housing said spring pressed ball and being slidably disposed within a vertical recess formed in the block carrying said ball, and means for holding said container in various adjusted positions in said recess.
5. A cap cleaning and stretching block, comprising a pair of side block sections for engaging into a cap and having their outer faces fashioned to the contour of the sides of said cap and having their inner faces sloping slightly inwards from the top to the bottom, a spreading forward central block section engaging between the forward ends of said side block sections and having its front face fashioned to the contour of the adjacent end of said cap and having its sides sloping inwards and engaging the inner faces of said side block sections for spreading the latter block sections and further having its rear face sloping rearwards from top to bottom, and a locking rear central block section engaging between the rearward ends of said side block sections and having its rear face fashioned to the contour of the adjacent end of said cap and having its sides sloping inwards and engaging the inner faces of said side block sections and further having its front face sloping rearwards from top to bottom and engaging the rear face of said forward central block section for spreading said central block sections and means for locking said rear central block section in position with relation to one of said side block sections to prevent its accidental disengagement from said cap comprising a spring pressed ball mounted in the side of one of said sections and engageable with a complementary recess formed in the other block section, a container housing said spring pressed ball and being slidably disposed within a vertical recess formed in the block carrying said ball, and means for holding said container in various adjusted positions in said recess comprising a releasable serrated strip engageable with a serrated flange formed on said container.

FRITZ GREIFENHAIN.
